(57) **CLAIM**

The ornamental design for a storage bin, as shown and described.

DESCRIPTION

FIG. 1 is a top front perspective view of the storage bin; FIG. 2 is a bottom front perspective view of the storage bin of FIG. 1;

FIG. 3: is a top view of the storage bin of FIG. 1; FIG. 4: is a bottom view of the storage bin of FIG. 1; FIG. 5: is a right-side view of the storage bin of FIG. 1, the left-side is a mirror image;

FIG. 6: is a front view of the storage bin of FIG. 1;

FIG. 7: is a rear view of the storage bin of FIG. 1;

FIG. 8: is a cross sectional view of the right-side of the storage bin of FIG. 1, the left-side is a mirror image;

FIG. 9: is a bottom front perspective view of the storage bin of FIG. 1 positioned on a shelf;

FIG. 10: is a bottom front perspective view of the storage bin of FIG. 1 positioned on a shelf; and,

FIG. 11: is a top perspective view of the storage bin of FIG. 1 positioned above a shelf.

The broken lines shown in the drawings illustrate unclaimed elements of the storage bin and environment and form no part of the claimed design.
